DESIGN FOR A CLOCK

Charles E. Murphy, Red Wing, Minn., assignor to
Mursen of Red Wing, Inc., Red Wing, Minn., a
corporation of Minnesota

Application August 25, 1947, Serial No. 141,045

Term of patent 3½ years

(Cl. D42—7)

To all whom it may concern:

Be it known that I, Charles E. Murphy, a citizen of the United States, residing at Red Wing, in the county of Goodhue and State of Minnesota, have invented a new, original, and ornamental Design for a Clock, of which the following is a specification, reference being had to the accompanying drawing, forming part thereof.

Fig. 1 is a front elevational view of a clock with the dial and hands shown in Fig. 2 omitted for convenience of illustration; and

Fig. 2 is a perspective view, on a reduced scale in comparison with the disclosure in Fig. 1, showing my new design.

I claim:

The ornamental design for a clock, as shown and described.

CHARLES E. MURPHY.
